UNITED STATES PATENT OFFICE.

PERCY J. CALLOWHILL, OF PROVIDENCE, RHODE ISLAND.

DESIGN FOR A COVER FOR A VANITY CASE OR SIMILAR ARTICLE.

Application filed March 28, 1927. Serial No. 21,368. Term of patent 7 years.

To all whom it may concern:

Be it known that I, PERCY J. CALLOWHILL, a subject of Great Britain, residing at Providence, in the county of Providence and State of Rhode Island, have invented new, original, and ornamental Design for Cover for a Vanity Case or Similar Article, of which the following is a specification, reference being had to the accompanying drawing, forming part thereof.

The drawing is a perspective view of the cover of a vanity case or similar article.

I claim:

The ornamental design for a cover for a vanity case or similar article as shown.

In testimony whereof I have signed my name to this specification.

PERCY J. CALLOWHILL.
